(57) **CLAIM**

The ornamental design for a holder for a battery-powered tool, as shown and described.

DESCRIPTION

This application may be related to subject matter disclosed in (i) U.S. design application Ser. No. 29/849,753 entitled "Holder for a battery-powered tool" application filed Aug. 14, 2022 in the name of Kenneth M. Wages (now U.S. Pat. No. D. 1,002,321), and (ii) U.S. non-provisional utility application Ser. No. 16/986,235 entitled "Holder for a battery-powered tool" filed Aug. 5, 2020 in the name of Kenneth M. Wages (now U.S. Pat. No. 11,446,809); both of said applications are incorporated herein by reference in their entireties.

FIG. 1 is a front view of a holder for a battery-powered tool showing my new design.

FIG. 2 is a back view thereof.

FIG. 3 is a top view thereof.

FIG. 4 is a bottom view thereof.

FIGS. 5 and 6 are side views thereof.

FIGS. 7 and 8 are upper perspective views thereof.

FIG. 9 is a front view of the holder for a battery-powered tool in use.

FIG. 12 is a front view of the holder for a battery-powered tool in use.

FIG. 13 is a side view of the holder for a battery-powered tool in use.

FIG. 14 is an upper perspective view of the holder for a battery-powered tool.

FIG. 15 is a lower perspective view of the holder for a battery-powered tool; and,

FIG. 16 is a lower perspective view of the holder for a battery-powered tool.

The claimed design shall encompass the holder for a battery-powered tool as shown in the drawings as well as mirror images thereof.

The broken lines depict environmental structure that forms no part of the claimed design.
